UNITED STATES PATENT OFFICE

2,428,822

PROOFREADING MACHINE

Robert van Sickler, Shreveport, La.

Application December 9, 1944, Serial No. 567,454

15 Claims. (Cl. 35—1)

1

This invention pertains to a proof-reading device for comparing typewritten matter but particularly to means for permitting the typed or otherwise inscribed matter to be matched.

Heretofore, in order to check the accuracy of typewritten or any kind of line for line work, it has been necessary for one person to read back from the original to a second person. Experience has proven, that after a comparatively short period of time, the tendency is for one or both to become drowsy and careless, thereby increasing the margin of error.

This invention contemplates not only the elimination of the second person but reduces the number of mistakes caused by earlier methods and in addition, permits the work to be completed in less time consumed by two people, and as a result puts the responsibility for accuracy upon the single individual performing the work.

While the present invention is primarily directed to comparison or matching of typewritten matter, it is obvious that many kinds of statistical data such as monthly insurance ledgers and payroll sheets of varying sizes may be expeditiously checked and compared by the present apparatus.

It is an object of my invention to enable typewritten matter to be matched or compared by a single operator.

Another object is to provide means for progressively disposing one sheet of typed matter, line for line, in close proximity with a second sheet of similar typed matter.

A further object is to provide means for adjustment for purposes of alignment of one sheet with another.

A still further object is to provide a receptacle for a plurality of sheets of paper to be compared so that the top sheet will always be in the desired plane.

Still another object is to provide means for isolating the lines on the two sheets of printed matter that are being immediately matched.

An additional object is to provide means for illuminating the desired lines of the two sheets that are being matched.

Another and still further object is to provide means for easy attachment and removal of the sheets of printed matter.

A further additional object is to provide means for mechanically advancing a sheet of typed matter, line for line, in close proximity with another sheet of typed matter for the purpose of matching or comparison.

Still another additional object is to provide

2

means for selectively advancing a sheet of typed matter one or more spaces for purpose of matching or comparison with a second sheet of typed matter.

Various other objects and advantages will be apparent from the following description of the accompanying drawings, which form a part of this disclosure and which illustrates a preferred form of embodiment of the invention.

10 The manner of accomplishing the foregoing objects, as well as further objects and advantages, will be made manifest in the following description, together with the accompanying drawings, in which:

15 Fig. 1 is a plan view of the manually operated device comprising a preferred embodiment of my invention.

Fig. 2 is a sectional view taken on the line 2—2 of Fig. 1.

Fig. 3 is a sectional view taken on the line 3—3 of Fig. 1.

Fig. 4 is a view similar to Fig. 1, showing the automatic operating means.

Fig. 5 is a side elevation of Fig. 4.

20 Fig. 6 is a sectional view taken on the line 6—6 of Fig. 4.

Fig. 7 is a fragmentary top plan showing a guard for the lines that are to be immediately compared.

25 Fig. 8 is an enlarged fragmentary sectional view taken on the line 8—8 of Fig. 7.

Figs. 9 and 10 are enlarged sectional views of the types of paper advancing members.

30 Fig. 11 is a sectional view of a modification of the paper advancing member within which is disposed illuminating means.

Fig. 12 is a fragmentary sectional view presenting supporting means for the member shown in Fig. 11 and the electrical connections therefor.

35 Fig. 13 is a diagrammatic view of the electrical circuit used in Figs. 11 and 12.

Fig. 14 is a reduced plan view similar to Fig. 1 of another modification of the invention showing a construction designed to facilitate the comparison of larger sheets of statistical matter of varying widths.

40 Fig. 15 is an end view similar to Fig. 5 of the modification shown in Figure 14.

In the drawings, wherein like reference characters denote like parts, the main support is indicated by the reference numeral 10. The central portion 12 is cut out to accommodate a paper receptacle 14. This receptacle is provided with side flanges to maintain a plurality of sheets of paper in stacked relation. Interposed between these

sheets of paper 18 and the bottom of the receptacle is a plate 20. Springs 22 are secured to the plate 20 and the bottom of the receptacle 14 to urge the top sheet of paper in the desired plane. A hinged flap 24 at the bottom of the receptacle can be utilized to enable easy insertion and removal of the papers from the receptacle. It is to be noticed that the height of the opening 12 is greater than the length of the receptacle thereby providing a space 18 at the top and/or bottom so as to permit vertical movement of the receptacle within said opening. A lever or handle 26 is shown to enable the receptacle to be moved vertically in the opening 12 for purpose of alignment which will be more fully explained later.

Secured at the top of the device is a support 28 for the paper securing means 30. In the present embodiment, a conventional spring controlled clamping construction is shown, although it is apparent that any type of paper holding means may be employed. This securing means 30 is designed to engage the top edge 32 of the sheet of paper 34 and has a length at least that of the width of the paper.

Grooves 36 are provided on the sides of the device to receive and permit movement of the supports 38 for the upper sheet engaging and advancing member 40. This member is shown as a circular shaft in Figs. 1 to 8, but it is also contemplated that flattened surfaces such as indicated in Figs. 9 to 11, will tend to position the line indicia to be compared in a plane comparable to that of the under sheet 18. A lever 46 is provided to facilitate movement of the operating member 40. A cut-out or reduced portion 48 is provided to enable the upper sheet 34 to be handled more expeditiously, as will be explained later in more detail.

In Figs. 4, 5 and 6, I have indicated mechanical means for the operation of the device. Grooves 50 and 52 are provided to receive the supports 54 and 56, allowing of vertical movement along the sides of the device. A tape, band or any other flexible member 58 is secured to the support 56 in any well known manner as at 60. This member 58 is also secured to the rotary member 62 located in an opening 63 at the bottom of the device and to a similarly rotatable device 64 controlled by a spring 65. The rotary member 62 is mounted on a shaft 66 which has a bearing 68 mounted on the opposite side. The rotary member 66 is similarly mounted on a shaft 70 positioned in an opening 67, having a bearing 72 mounted on the opposite side of the device.

Keyed at 69 to the shaft 66 on one side of the main support 10 is a ratchet wheel 74. Pivotally mounted on a shaft 76 is an operating member 78 having a lever 80. A pawl 82, having a cam stop 83 is secured to shaft 76, but lying in the same plane as the ratchet wheel 74 and adapted to have cooperative engagement therewith and held in engagement by the spring 84. Limited movement of the opposed arm 86 of the pawl 82 is had by means of a stop 88 positioned in its path. Adjustment of this limitation is accomplished by the positioning of the stop plug 88 in any one of the openings 90, 92 or 94. Another pawl 96 is mounted at 98 on the operating member 78 and is continually urged into engagement by a spring 100. This pawl is prevented from dropping out of position by the stop 101 when the operating member 78 is lifted out of engagement to return the member 40 to initial position. Excessive vertical movement of the member 78 is prevented by spring 102 secured to flange 104 on

member 78 and to a support 106 mounted on the side of the device. Operation of the above construction will be explained later, the associated structure otherwise being the same as described in Figs. 1, 2 and 3.

In Figs. 7 and 8, a modification shows means for accentuating the two lines that are to be immediately compared. A plate 108 is hinged at 110 to the member 40 although it is conceivable that it could be attached to the support 38. An opening 112 is provided so that, in effect, the other lines of type or indicia are diminished in importance. Any conventional means, as indicated at 114 may be used to enlarge the opening 112 to permit more than one line of type to be viewed.

Fig. 8 is an enlarged sectional view of the top of the device to more clearly indicate the relationship of the two sheets of paper. The top of the second sheet 34 is attached to the securing member 30 and then folded under the member 40 but above the first sheet. The bottom of the second sheet then extends outwardly from the top of the device made easy by the reduced portion 48.

In Figs. 9 and 10, I have shown enlarged sectional views of modifications 40' and 40'', of paper engaging members. It has been found that either of these constructions will more readily flatten out the sheet 34 after engagement with the fold or bight 35 and upon its movement down the sheet, the underneath portion of the sheet will progressively come into view adjacent the desired lines of the first sheet. For purpose of matching or comparison, it is an objective to have the desired lines of each sheet to lie as nearly as possible in the same plane.

Figs. 11, 12 and 13 show a modification which permits of illumination of the lines to be viewed. The well known properties of Lucite readily lend themselves to application in the present invention. In the enlarged sectional view of Fig. 11, I have shown the paper engaging and advancing member 40''' made of Lucite and having a covering or black-out substance 119 to enclose this member with the exception of the opening 112'. It is apparent, when illuminating means, such as the incandescent lamp 116 is positioned within the longitudinal opening 118, only the desired lines of both sheets 18 and 34 will be accentuated.

Diagrammatic views of the illuminating means 116 and sliding contacts are shown in Figs. 12 and 13. The sliding member 38' is shown positioned in the groove 36' and is provided with contact plates 120 while the groove 36' is provided with contact plates 122 extending the length of the device. A battery is indicated at 124. By this means, a movable electrical connection is provided to illuminate the paper engaging and advancing member 40''' as it moves down the sheet. A conventional switch may be employed to eliminate the light when not required.

In Figures 14 and 15, the main support 10', the central portion 12', and the receptacle 14', have been increased longitudinally to permit the reception of paper having greater widths, for example payroll sheets of a size in excess of legal or correspondence sized paper. In order to accommodate the larger width paper, the length of the advancing member 40' has also been increased, although the supports 38 and the groove construction remain the same.

The securing means 30 for the top edge of the papers is slidably mounted on shaft 33, secured to supports 35' at the outer edges at the top surface of the machine. The paper securing means 30 may be positioned and held in place by a

winged nut or other securing means 31, which construction permits of slidable longitudinal movement along shaft 33 to align the inscribed matter or indicia *d* on the paper 34 held in position by member 31 with the selected column of inscribed matter or indicia *a*, *b*, or *c*, on the master sheet 18 in receptacle 14.

For example, if a master statistical sheet having a plurality of columns of statistical or typed matter identified thereon, as at *a*, *b* and *c*, and it is desirable to compare the data *d* appearing on sheet 34 with comparable selected data *b* on the master sheet, the sheet 34 is secured to member 30 which is positioned directly above typed matter *b*, and secured in place by means of member 31. The comparable printed matter on these sheets is aligned by moving the member 30 along the shaft 33 in either direction.

Operation.

With particular reference to Figs. 1, 2 and 3, the sheets of paper 18 are placed in the receptacle 14, the top sheet always lying in approximately the same plane as the top face of the device due to the action of the spring controlled plate 20. The companion sheet to the first sheet of the stack is secured at its top edge to the spring controlled clamping member 30 and then folded under the member 40 with the major portion of the sheet at the outset, lying underneath the secured top edge but face down over the upper portion of the top sheet 18.

The handle is then manually moved downwardly until the first lines of each of the two sheets are in close proximity to each other. In the event there is a slight misalignment, the receptacle 14 is moved by operation of the handle 26 until complete alignment is had. Continued movement of the member 40 will automatically cause the related lines of each sheet to be disposed adjacent each other as the upper sheet is unfolded or advanced down over the under sheet. Upon completion, the top sheet of the plurality of sheets 18 is removed from the stack and another sheet, companion to the one now on the top of the stack, is substituted for the one secured to the member 30.

It is to be observed, that not only is the device capable of having the typed sheets compared by reading, but unconsciously the operator will match the words without reading. It is readily apparent, that when a word or a letter is incorrect, the error will stand out boldly as is indicated at 126 in Figs. 1 and 7.

As previously suggested, it is most important that the related lines of indicia or typed matter stand out from the remaining lines on the sheet. This objective is obtained by illumination, isolation and by the disposition of the desired line on the upper sheet 34 in a plane nearly to that of the under sheet as possible, that condition being maintained as the edge or fold 35 advances downwardly to the last line.

In the mechanical construction shown in Figs. 4, 5 and 6, it is not necessary that the operator manually advance the member 40 down the sheet. After setting the selective control for one, two or three lines or spaces, operation of the lever 80 will cause the step by step travel of the member 40 to the bottom. Initial adjustment may be had by manipulation of the handle 26 positioned at the bottom of the device.

It is to be appreciated that downward motion of the lever 80 will cause the pawl 96 to advance the ratchet wheel 74 one tooth which will,

in turn, advance the member 40 secured to the tape 58 one space. The arm 86 will then strike the plug 88, the pawl 82 dropping behind the next tooth and its adjacent tooth resting on the stop 83, thereby preventing an overthrow. Release of the lever will enable the spring 102 to return it to inoperative position. In Fig. 5, the lever is shown in position to advance the ratchet wheel one tooth. Positioning of the plug 10 88 in one of the openings 90, 92 or 94, will govern the movement of the lever 80 to advance the member 40, single, double or triple spaces.

In order to return the member 40 to its initial position, the lever 78 is manually raised to release the pawls from engagement and the paper advancing member automatically returns to initial position under the control of the spring 65.

I claim:

1. In a device for comparing two sheets having 20 lines of indicia, a receptacle for the first sheet of paper, securing means for the second sheet of paper mounted on said receptacle adapted to secure said second sheet at an edge, a moving member adapted to engage the bight of said second sheet to progressively bring into view a line of indicia at a location immediately adjacent the corresponding line of indicia on said first sheet to permit of ready comparison.

2. In a device for comparing two sheets having 30 lines of indicia, a receptacle for the first sheet of paper, securing means for the second sheet of paper mounted on said receptacle adapted to secure said second sheet at an edge, a moving member adapted to engage the bight of said second sheet to progressively bring into view a line of indicia at a location immediately adjacent the corresponding line of indicia on said first sheet to permit of ready comparison, and means for accentuating the lines of indicia being compared.

3. In a device for comparing two sheets having 45 lines of indicia, a receptacle for the first sheet of paper, securing means for the second sheet of paper mounted on said receptacle adapted to secure said second sheet at an edge, a moving member adapted to engage the bight of said second sheet to progressively bring into view a line of indicia at a location immediately adjacent the corresponding line of indicia on said first sheet to permit of ready comparison, means for accentuating the lines of indicia being compared, and means for aligning the comparable lines of indicia.

4. In a device for comparing two sheets having 55 lines of indicia, a receptacle for the first sheet of paper, securing means for the second sheet of paper mounted on said receptacle adapted to secure said second sheet at an edge, a moving member adapted to engage the bight of said second sheet to progressively bring into view a line of indicia at a location immediately adjacent the corresponding line of indicia on said first sheet to permit of ready comparison, means for accentuating the lines of indicia being compared, means for aligning the comparable lines of indicia, and means for urging the first sheet of paper into close relationship with that portion of said second sheet nearest to said first sheet lying in the same plane.

5. In a proof-reading machine for typed or otherwise inscribed matter, means for positioning two or more sheets of inscribed matter in close proximity to each other including a receptacle for one or more sheets and a holding member mounted adjacent said receptacle for secur-

ing a second sheet at an edge, and means for progressively bringing into view a line of inscribed matter on said second sheet and into matching relationship with the corresponding line on said first sheet comprising a moving member adapted to engage the bight of said second sheet to facilitate easy comparison.

6. In a proof-reading machine for typed or otherwise inscribed matter, means for positioning two or more sheets of inscribed matter in close proximity to each other including a receptacle for one or more sheets and a holding member mounted adjacent said receptacle for securing a second sheet at an edge, and means for progressively bringing into view a line of inscribed matter on said second sheet and into matching relationship with the corresponding line on said first sheet comprising a moving member adapted to engage the bight of said second sheet to facilitate easy comparison, and means for vertically and horizontally aligning said lines of inscribed matter.

7. In a proof-reading machine for typed or otherwise inscribed matter, means for positioning two or more sheets of inscribed matter in close proximity to each other including a receptacle for one or more sheets and a holding member mounted adjacent said receptacle for securing a second sheet at an edge, and means for progressively bringing into view a line of inscribed matter on said second sheet and into matching relationship with the corresponding line on said first sheet comprising a moving member adapted to engage the bight of said second sheet to facilitate easy comparison, and means for vertically and horizontally aligning said lines of inscribed matter, and means for accentuating the lines that are being immediately compared.

8. In a proof-reading machine for typed or otherwise inscribed matter, means for positioning two or more sheets of inscribed matter in close proximity to each other including a receptacle for one or more sheets and a holding member mounted adjacent said receptacle for securing a second sheet at an edge, and means for progressively bringing into view a line of inscribed matter on said second sheet and into matching relationship with the corresponding line on said first sheet comprising a moving member adapted to engage the bight of said second sheet to facilitate easy comparison, and means selectively operable for causing movement of said receptacle upwardly or downwardly with respect to said second sheet holding means.

9. In a proof-reading machine for typed or otherwise inscribed matter, means for positioning two or more sheets of inscribed matter in close proximity to each other including a receptacle for one or more sheets and a holding member mounted adjacent said receptacle for securing a second sheet at an edge, and means for progressively bringing into view a line of inscribed matter on said second sheet and into matching relationship with the corresponding line on said first sheet comprising a moving member adapted to engage the bight of said second sheet to facilitate easy comparison, means selectively operable for causing movement of said receptacle upwardly or downwardly with respect to said second sheet holding means, and means for returning said moving member to its initial position.

10. In a proof-reading machine for typed or otherwise inscribed matter, means for positioning two or more sheets of inscribed matter in close

proximity to each other including a receptacle for one or more sheets and a holding member mounted adjacent said receptacle for securing a second sheet at an edge, and means for progressively bringing into view a line of inscribed matter on said second sheet and into matching relationship with the corresponding line on said first sheet comprising a moving member adapted to engage the bight of said second sheet to facilitate easy comparison, means selectively operable for causing movement of said receptacle upwardly or downwardly with respect to said second sheet holding means, means for returning said moving member to its initial position, and ratchet means for enabling step by step movement of said moving member.

11. In a proof-reading machine for typed or otherwise inscribed matter, means for positioning two or more sheets of inscribed matter in close proximity to each other including a receptacle for one or more sheets and a holding member mounted adjacent said receptacle for securing a second sheet at an edge, and means for progressively bringing into view a line of inscribed matter on said second sheet and into matching relationship with the corresponding line on said first sheet comprising a moving member adapted to engage the bight of said second sheet to facilitate easy comparison, means selectively operable for causing movement of said receptacle upwardly or downwardly with respect to said second sheet holding means, means for returning said moving member to its initial position, ratchet means for enabling step by step movement of said moving member, and a spring for urging said first sheet in a plane closer to said second sheet.

12. In a proof-reading machine for comparing two sheets having indicia thereon, a receptacle for two or more sheets of inscribed paper, a holding member for a second sheet at an edge mounted adjacent said receptacle, means for progressively bringing into view a line of inscribed matter on said second sheet and into matching relationship with the corresponding line on one of said first mentioned sheets comprising an adjustable moving member adapted to engage the bight of said second sheet to permit of easy comparison.

13. In a proof-reading machine for comparing two sheets having indicia thereon, a receptacle for two or more sheets of inscribed paper, a holding member for a second sheet at an edge mounted adjacent said receptacle, means for progressively bringing into view a line of inscribed matter on said second sheet and into matching relationship with the corresponding line on one of said first mentioned sheets comprising an adjustable moving member adapted to engage the bight of said second sheet to permit of easy comparison, and ratchet means for enabling step by step movement of said moving member.

14. In a proof-reading machine for comparing two sheets having indicia thereon, a receptacle for two or more sheets of inscribed paper, a holding member for a second sheet at an edge mounted adjacent said receptacle, means for progressively bringing into view a line of inscribed matter on said second sheet and into matching relationship with the corresponding line on one of said first mentioned sheets comprising an adjustable moving member adapted to engage the bight of said second sheet to permit of easy comparison, ratchet means for enabling step by step movement of said moving member, and means oper-

able for causing longitudinal movement of said second sheet holding means to selectively position said second sheet directly over one of said first mentioned sheets.

15. In a proof-reading machine for comparing two sheets having indicia thereon, a receptacle for two or more sheets of inscribed paper, a holding member for a second sheet at an edge mounted adjacent said receptacle, means for progressively bringing into view a line of inscribed matter on said second sheet and into matching relationship with the corresponding line on one of said first mentioned sheets comprising an adjustable moving member adapted to engage the right of said second sheet to permit of easy comparison, ratchet means for enabling step by step movement of said moving member, means operable for causing longitudinal movement of said

second sheet holding means to selectively position said second sheet directly over one of said first mentioned sheets, and means for returning said moving member to its initial position.

ROBERT VAN SICKLER.
